UNITED STATES PATENT OFFICE.

HENRY E. WHITAKER AND JAMES M. MACDONALD, OF DETROIT, MICHIGAN, ASSIGNEES TO PARKE, DAVIS & COMPANY, OF DETROIT, MICHIGAN, A CORPORATION OF MICHIGAN.

APPARATUS FOR FORMING MEDICINAL TABLETS.

1,102,374.

Specification of Letters Patent.

Patented July 7, 1914.

Application filed March 9, 1908. Serial No. 420,097.

To all whom it may concern:

Be it known that we, HENRY E. WHITAKER and JAMES M. MACDONALD, citizens of the United States of America, residing at 5 Detroit, in the county of Wayne and State of Michigan, have invented certain new and useful Improvements in Apparatus for Forming Medicinal Tablets, of which the following is a specification, reference being 10 had therein to the accompanying drawings.

The invention relates to machines for forming tablets, and it is the special object of the invention to obtain a construction which is adapted for forming medicinal tablets either friable or hard compressed. 15

To this end the invention consists in certain features of construction as hereinafter set forth.

In the drawings— Figure 1 is a vertical 20 longitudinal section through the machine; Fig. 2 is a cross-section substantially on the line α — α of Fig. 1, certain parts being omitted.

In the present state of the art medicinal tablets of the soft friable variety are formed by a hand process, while the compressed tablets are formed mechanically. The hand process is one necessitating the mixing of the dry ingredients with alcohol to form a 25 plastic compound, the filling of the perforated mold plates with this plastic substance by the use of a spatula, the drying and hardening of the material in the mold cavities by dusting in dry powder over the surface 30 of the plate and scraping it in with the spatula, and finally the ejection of the molded tablets from the plates. This process is a slow one, requiring a certain degree of 35 skill on the part of the operator and necessitating the use of alcohol as a moistening 40 agent. On the other hand, the compressed tablets, while they may be formed by mechanically driven and automatically operated 45 presses, require for their manufacture a granulated material, and this necessitates a long and expensive process of the treatment of the ingredients before the material 50 is ready for the press.

With the machine forming the subject 55 matter of the present invention the tablets may be formed from the mixed ingredients by slight moistening of the mixed dry materials, and for the moistening agent water may be employed, instead of alcohol.

Broadly considered, the machine comprises means for distributing the material over the mold plates, together with means for mechanically pressing the distributed material into the mold cavities and for scraping off from the surface the surplus 55 material.

The machine further comprises mechanism for ejecting the tablets from the mold cavities and, where the compressed tablets are to be formed, further includes compressing dies and operating mechanism therefor. 60

One of the difficulties encountered in the manipulation of the materials of which the tablets are formed is the tendency to adhere to any surface coming in contact therewith. 65 It is also necessary to distribute a uniform amount of the material into each of the mold cavities, and to impart to each tablet the same degree of compression. To meet these conditions, the machine comprises as one of 70 its essential features mechanism for moving a blade a portion of which is inclined over the surface of the mold plate upon which the tablet material has been deposited while said plate is resting upon a bed or table, the operation of the blade being to simultaneously 75 force the material into the mold cavities and to scrape off the surplus material. In performing this function there is a tendency to compress the material to a greater degree 80 upon the side of the mold cavity toward which the inclined blade is moved, and to avoid this result a second blade having an oppositely inclined portion is preferably employed, this being moved over the plate in 85 reverse direction. The relative movement of the blades and the mold plate may be accomplished in different ways, but preferably 90 is effected by mounting the blades upon revoluble members and by feeding the plates 95 beneath said revoluble members.

In detail A is a suitable frame or bed provided with guideways B for the movable mold plates C. These plates are fed along the guides by suitable feeding mechanism, such as the rolls D D', which frictionally engage the plates as they are introduced at one end of the machine, feeding them over the bed and propelling the plates to advance as they are disengaged from the 105 rolls. Adjacent to the rolls D D' is arranged a hopper, or other receptacle, E containing the material forming the tab-

lets. This material has been previously mixed and moistened and the hopper E preferably contains an agitator, such as the revoluble member F, for assisting the uniform deposit of the material on the mold plates. Beyond the member F is a filling and distributing roll G which gages the height of the material deposited on the plates, and also presses it into the mold 5 cavities. The surface of this roll is of any suitable material, such for instance as celluloid, to which the moistened material will not readily adhere.

H and I are two oppositely revoluble 10 shafts extending across the bed above the path of the mold plates and journaled in suitable bearings in the frame. Each of these shafts has secured thereto a series of radially extending plates J, these being 15 preferably formed of resilient material and being preferably also slightly curved. The blades carried by the shafts H travel in the same direction as the mold plates, but at a higher rate of speed, while the blades 20 on the shaft I travel in the opposite direction. Thus the former will press the material which covers the surface of the plates downward and into the mold cavities, and will then scrape over the surface of the 25 plates to remove the surplus material, throwing it forward or in the direction that the mold plate is traveling. The blades upon the shaft I have a similar action upon the material which has been thrown forward by the other blades, and the combined 30 action of the two sets of blades is to accumulate the surplus material in a triangular pocket between the shafts H and I. The material is prevented from being 35 thrown over the shafts H and I and the blades are also cleaned by scrapers K, which are arranged to bear upon each of the blades, as they rotate to disengage any adhering material therefrom.

40 The plates after passing beneath the shaft I are fed forward at an accelerated speed by a pair of feed rollers L L', and this is for the purpose of permitting each plate to remain stationary for an interval during 45 which the tablets are ejected. The ejector mechanism comprises a vertically reciprocating head M, which is provided with downwardly extending pins N that register with the mold cavities in each of 50 the mold plates C, during the interval in which it is stationary beneath the head M. The descent of this head will cause the pins N to force the tablets downward from the mold cavities, and at this point the bed of 55 the machine is cut away to permit the disengaged tablets to drop upon a receiving plate or carrier O.

60 Where oval or other fashioned tablets are to be formed this operation is effected while 65 the material is still in the mold cavities and

after the plates have passed beyond the scrapers. If desired, this forming mechanism may be combined with the ejector mechanism, the head M having a portion M' thereof for holding one of the compression dies and a second compression die P being arranged beneath the plate and being moved forward as the head M is moved downward.

Any suitable form of gearing may be employed for driving the various parts of the mechanism above referred to in proper timing relation. As shown, motion is first communicated to the main drive shaft Q by a suitable belt engaging tight and loose pulleys upon this shaft. This shaft Q drives the rolls L L' through the medium of a gear train R, and drives the shafts H and I through a gear train S. The rolls D D' are driven through the gear train S and a 75 sprocket and chain connection T, and the roll G is driven from the shaft of the roll D by a sprocket or belt connection U. The ejector and compressor mechanism is operated through a gear train V from the shaft 80 Q, which drives a shaft W, having eccentrics X and Y thereon, which are respectively connected to operate the heads M and P.

In operation, the moistened material is placed in the hopper E and is driven over 85 the plates as they are fed forward by the rolls D D', while the roll G, which is preferably driven at the same speed as the plate, gages the depth of the deposit and presses it down to fill the mold cavities. As the plates 90 continue their forward movement, they first pass beneath the shaft H and into the path of the rotating blades J carried thereby. These blades are curved, as described, and rotate to press the convex surface against 95 the material on the plates forcing it downward into the mold cavities until the edge of the blade J comes in contact with the upper surface of the plate C. The blade will then be caused to scrape over the surface of the 100 plate, the resiliency of the material of the former permitting this operation. A similar action takes place as the plates C are fed beneath the shaft I, the only difference being that in the first case the pressure exerted 105 on the material is toward the forward side of the mold cavity and in the latter case toward the rear side thereof. The effect will be to produce a uniform density in all portions of the tablets, and the operation of 110 the blade J' on the shaft I will produce a smooth upper surface. The lower surface of the tablet is formed by sliding over the bed or table upon which the plates C are moved, and thus when the ejector mechanism 115 is reached the tablets are in condition for disengagement.

120 It is to be noted that the operations performed by this machine differ from those of the usual hand process. In the latter, the 125

material must be moistened to a much greater extent so as to form a sufficiently plastic mass to be filled into the mold cavities with the spatula. This moist material takes a considerable time interval to dry, and it is therefore necessary for the operator to dust dry powder over each face of the mold plate working it in to the mold cavities with the spatula, and thereby drying and hardening the tablets before they can be ejected. In the operation of the machine, the material has but a limited amount of moisture therein, so that it can only be forced into the mold cavities by the exertion of considerable pressure. This pressure is produced by the action of the blades and, as they are traveling at a higher rate of speed than the movement of the plate C, a series of these blades will successively operate upon the material for each row of tablets. Thus, after the cavities are filled, and the surplus material scraped off, the tablets are in condition to be immediately ejected without requiring the intermediate step of dusting in dry powder. The operation of the blades J J' in the opposite direction causes the accumulation of a quantity of the material therebetween, and to remove this material a transversely extending screw conveyer or equivalent device Z is arranged between the shafts H and I. This in operation will carry away the accumulated material which may be returned to the hopper E.

What we claim as our invention is:

35 1. In an apparatus for forming medicinal tablets, a mold plate having a series of mold cavities therein, a roll extending transversely of the mold plate for depositing a uniform layer of material over the latter, a blade, 40 and means for operating said blade to scrape and knead the material into the mold cavities.

2. In an apparatus for forming medicinal tablets, a mold plate having a series of mold cavities therein, means for depositing material upon said plate, a plurality of revolving blades, a portion of said blades being inclined in the direction of said blades' travel for pressing and scraping the material into 50 the mold cavities.

3. The combination with a mold plate having a series of mold cavities therein, of means for depositing the material upon said plate, means for scraping the material in opposite directions over said plate, and means for removing the surplus material accumulated by said scraping means.

4. The combination with a mold plate having a series of mold cavities therein, of a bed over which said plate is fed, means for depositing the material upon said plate, a pair of oppositely rotating members above said bed, scrapers carried by said rotating members and moved thereby across said plate when moved over said bed to force the

material on said plate into said mold cavities, and means for removing the surplus material accumulated by said scrapers.

5. The combination with a bed, of a series of mold plates adapted to be successively fed over said bed, each plate being provided with a series of mold cavities, means for depositing the material upon said plates, a revolving blade for forcing the deposited material into the mold cavities, and for removing the surplus material, and an ejector for disengaging the molded tablets from said plates. 70

6. The combination with a bed, of a series of mold plates, each provided with a series of mold cavities, means for feeding said mold plates successively over said bed, means for depositing material on the surface of each mold plate, a gage for determining the depth of the material thus deposited, oppositely revolving blades for pressing and scraping the material into the mold cavities, and means for ejecting the molded tablets. 80

7. The combination with a mold plate having a series of mold cavities therein, of means for depositing material upon said plate, a roll for pressing the material against the plate and into the mold cavities thereof, a blade having an inclined portion, and means for moving said blade over the surface of said plate to further press the material into the mold cavities and removing the surplus material from the surface of the plate. 90

8. The combination with a mold plate having a series of apertures extending therethrough, of a bed, means for feeding said plate over said bed, means for depositing the material on the surface of said plate, means for pressing the deposited material against the plate to force it into the mold cavities thereof, means for drawing an inclined scraper over the plate to further force the material into the mold cavities and to remove the surplus material, a forming die for fashioning the molded material while still in the mold cavities of said plate, and an ejector for disengaging the completed tablet. 100

9. The combination with a bed or table, of a mold plate having a series of mold cavities therein, means for feeding said plate over said bed or table, means for depositing material upon said plate, a roll for pressing the deposited material against said plate and into the mold cavities thereof and for gaging the depth of the material upon the plate, a rotary member having a series of scrapers successively drawn over the surface of said plate, a forming die for fashioning the tablets while in the mold cavities and an ejector for disengaging said tablets. 110

10. The combination with a mold plate having a series of mold cavities therein, of means for depositing a uniform layer of material over said plate, a series of revolving

- blades, means for revolving said blades in opposite directions, and in inclined relation thereto to force the material into the mold cavities.
11. The combination with a movable mold plate having a series of mold cavities therein, of a member mounted for rotation above said plate, a series of resilient spatula-shaped blades carried by said member and means for feeding said mold plate across the path of movement of said blades and transverse thereto, for the purpose described.
12. The combination with a movable mold plate having a series of mold cavities therein, of a revolving blade partially inclined in the direction of travel of said blade for pressing and scraping the material into the mold cavities.
13. In an apparatus for forming medicinal tablets, a mold plate having a series of
- mold cavities therein, a plurality of revolving blades partially inclined in the direction of travel of said blades for pressing and scraping the material into the mold cavities.
14. In an apparatus for forming medicinal tablets, a mold plate having a series of mold cavities therein, means for depositing a uniform layer of material over said plate, a blade for forcing the material into the mold cavities, means for moving said blade over the surface of said plate in inclined relation thereto, and an ejector for disengaging the tablets from the mold cavities.

In testimony whereof we affix our signatures in presence of two witnesses.
